Patented Oct. 29, 1912.

UNITED STATES PATENT OFFICE.

JOHN H. McCONNELL, OF WINSLOW, INDIANA.

MUSTACHE-GUARD.

1,042,940.

Specification of Letters Patent.

Patented Oct. 29, 1912.

Application filed January 25, 1912. Serial No. 673,429.

To all whom it may concern:

Be it known that I, JOHN H. McCONNELL, a citizen of the United States, residing at Winslow, in the county of Pike and State 5 of Indiana, have invented certain new and useful Improvements in Mustache-Guards; and I do declare the following to be a full, clear, and exact description of the invention, such as will enable others skilled in the art 10 to which it appertains to make and use the same.

This invention relates to improvements in mustache guards.

One object of the invention is to provide 15 a guard of this character which may be readily applied to and removed from the mustache and which when applied will effectually cover and protect the mustache while eating or drinking so that the food 20 or liquid will not come in contact with the same.

Another object is to provide a device of 25 this character which will be simple and inexpensive in construction, efficient in operation and which when not in use may be folded and readily carried in the pocket.

With these and other objects in view, the 30 invention consists of certain novel features of construction, and the combination and 35 arrangement of parts as will be more fully described and claimed.

In the accompanying drawings: Figure 1 is a perspective view showing the application 35 of the invention; Fig. 2 is a perspective view of the guard with the parts in an open position; Fig. 3 is a plan view of the parts in closed position; Fig. 4 is a cross sectional view of the guard with the parts as shown in Fig. 2; Fig. 5 is a similar view with the 40 parts as shown in Fig. 3; Fig. 6 is a detail perspective view of the hinged connecting bar and spring for connecting the sections of the inner members together and for holding the outer members in operative and in- 45 operative positions.

My improved mustache guard comprises inner mustache engaging members 1 which are in the form of combs and which are adapted to be placed against the lip, and the 50 teeth thereof pushed upwardly through the mustache. The members 1 are adjustably and hingedly connected together at their inner end by a narrow connecting bar or plate 2 formed in hingedly connected sections in 55 which are formed longitudinally disposed slots 3 with which are engaged headed studs

4 secured to and projecting from the outer side of the members 1 and through the slots 3 as shown. On the outer ends of the members 1 are formed longitudinally extending outwardly curved lugs 5 which provide handles whereby the members 1 are engaged with and disengaged from the mustache. The hinged connection of the members 1 will permit the same to conform to the curvature 60 or shape of the lip and when the guard is not in use will permit the same to be folded together end to end and readily carried in the pocket.

Hingedly connected to the lower edge of 70 the members 1 and adapted to co-act therewith to hold the guard in position are clamping members 6, said members also being preferably in the form of combs. The teeth 7 of the combs or members 6 are of 75 slightly less length than the teeth of the members 1 and said teeth 7 are disposed opposite to the spaces between the teeth of the members 1 and are curved or concaved to fit around the hairs of the mustache when 80 gathered or bunched together by the members 1. The outer ends of the teeth 7 of the members 6 and the teeth of the members 1 are bent outwardly to a slight extent to prevent said ends from coming into engagement 85 with the lip when the members 8 are brought into operative position.

The slotted bars of plates 2 of the guard are provided with suitable springs 8 or similar devices whereby when said mem- 90 bers are swung down or inwardly, the same will be held in yielding engagement with the outer side of the mustache, thus clamp- 95 ing the latter between said members and the inner members 1. The springs 8 also serve 95 to hold the members 6 in an upright position at right angles to the members 1, while the guard is being engaged with the mustache. The springs 8 are preferably formed integral with the sections of the connecting 100 bar 2 as shown. On the outer ends of the members 6 are formed longitudinally ex- 105 tends outwardly curved lugs 9 which provide handles whereby the members 6 may be opened or closed.

The parts of the hinge connection of the clamping members 6 have formed therein short, spirally disposed slots 6^a with which are engaged pins 6^b on the pintles or pivot rods 6^c which are fixed to the hinge connec- 110 tion of the members 1 whereby when said clamping members 6 are closed or swung

up into engagement with the comb members said clamping members 6 will slide outwardly to a slight extent, which action of the clamping members will tend to smooth or straighten out the hairs of the mustache.

In applying the guard the teeth of the inner members 1 are placed against the upper lip and said members pushed upwardly thus engaging the teeth with the mustache.

- 10 After the members 1 have thus been engaged with the mustache and the hairs thereof pushed upwardly or bunched together said members are gently pulled laterally or outwardly to a slight extent to 15 draw the hairs down after which, the clamping members 6 are swung up into engagement with the outer side of the mustache, thus clamping the latter between the members 1 and the members 6 whereby the hairs 20 of the mustache are held up in an out of the way position while eating or drinking.

In order to remove the guard the lugs 5 of the outer ends of the members 1 are 25 grasped between the thumb and finger of each hand and the thumbs forced between the lugs 5 and the lugs 9 of the clamping members 6, thus lifting said members to a slight extent whereupon a gentle downward 30 pull on the guard will disengage the teeth of the members 1 from the mustache. When not in use the clamping members 6 are swung up into engagement with the inner members 1 whereupon the guard may be readily 35 folded and carried in the pocket or inserted in a suitable case similar to a spectacle case.

From the foregoing description taken in connection with the accompanying drawings, the construction and operation of the invention will be readily understood without requiring a more extended explanation.

40 Various changes in the form, proportion and the minor details of construction may be resorted to without departing from the principle or sacrificing any of the advantages of the invention as claimed.

45 Having thus described my invention, what I claim is:—

In a mustache guard, a pair of comb like mustache engaging members, a pair of comb like clamping members hingedly connected 50 to said mustache engaging members and adapted to be swung up into engagement with the mustache whereby the latter is clamped between said members and the inner mustache engaging members, said 55 clamping members being adapted to move outwardly while being swung up into operative position thereby smoothing the hairs of the mustache, and springs secured to said 60 mustache engaging members and adapted to engage the clamping members whereby the latter are yieldingly held in operative or inoperative position.

In testimony whereof I have hereunto set my hand in presence of two subscribing witnesses.

JOHN H. McCONNELL.

Witnesses:

LON WILLIAMS,
C. E. BEE.
